UNITED STATES PATENT OFFICE

JOHN M. LARSON, OF CHICAGO, ILLINOIS, ASSIGNOR TO NATIONAL REGULATOR COMPANY, OF CHICAGO, ILLINOIS, A CORPORATION OF ILLINOIS

REGULATOR

Application filed April 14, 1930. Serial No. 444,184.

My invention relates to regulators and more specifically to regulators for controlling combustion by means of the draft pressure.

5 Among the objects of my invention are to provide a regulator of the type which will have a graduated action, to provide a dust-proof construction for the inverted cup or bell, to provide anti-friction centering means 10 for the bell, to provide an adjustable and alignable lever arrangement between the bell and relay valve, to improve various features of construction, to provide a simple block or relay valve in which the slightest movement 15 in either direction will open the supply or exhaust and in which one port must be closed before the other can open, and in which the sensitiveness is not changed by wear, and to provide renewable elements for the valve construction.

20 Further objects will appear from the description and claims.

In the drawings, in which an embodiment of my invention is shown—

25 Figure 1 is a side elevational view showing my improved regulator controlled by the draft pressure and controlling the uptake damper of the furnace for a steam boiler;

Fig. 2 is a perspective view showing the 30 power cylinder, pilot or relay valve and pressure-operated controller for the relay valve; and

Fig. 3 is a vertical axial section through the power cylinder and relay valve.

35 Referring to the drawings in detail, the construction shown comprises a steam boiler and furnace 1, having an uptake damper 2, a power cylinder 3 for controlling the position of the uptake damper 2 and mechanism 40 controlled by the draft pressure (that is to say, the pressure above the fire bed) for controlling the connection of pressure and exhaust with the power cylinder 3. In order to give a general idea of the operation, it is 45 here stated that an increase in the draft pressure (that is to say, an increase in suction) will set in action a train of forces, the final effect of which is to tend to close the uptake damper 2, thus tending to maintain a uniform 50 balanced draft pressure. Conversely, a de-

crease of draft pressure (that is to say, a decrease of suction) will tend to open the uptake damper 2 and increase the draft suction.

In general, the control for the movement of the power cylinder 3 comprises a relay valve construction 4 having valve mechanism which, in raised position, connects the cylinder 3 with compressed air or steam and which in lowered position connects the cylinder 3 with exhaust, this control valve mechanism being raised when the bell or inverted cup 5 connected with the draft pressure is lowered and conversely the valve mechanism being lowered when the bell 5 is raised. The lower edge 6 of this bell or inverted cup 5 is immersed in a suitable liquid 7, such as oil contained in the annular chamber between the inner and outer shells 8 and 9, the interior of the inverted cup being in communication with the draft pressure 70 through the conduit 10. The interior of the bell is also in communication with a draft gauge which will indicate the draft pressure by means of a vertical pipe 11 extending up into the space inside the inner shell 8 and a conduit 12 in communication with this vertical pipe 11. The provision of the vertical pipe 11 prevents the entry of foreign substances, such as oil, dust and the like from getting into the draft gauge tube because 80 of the fact that the entrance to this pipe is well above the bottom 13 of the chamber within the inner shell 8. A suitable liquid level indicator 14 may be provided for showing the height of the oil in the annular chamber. In order that the bell 5 may move freely and easily up and down, I provide a plurality of anti-friction rollers 15 secured to the outer shell 9, the rollers themselves being engageable with the outer surface of 90 the bell.

The transmission from the bell 5 to the relay valve mechanism comprises a lever 16 pivotally mounted on a standard 17 at 18 and a second lever 19 pivotally mounted on an adjustable bracket 20 at 21 and pivotally connected with a spring rod 22 formed as an integral part of the valve stem 23. In order to facilitate the alignment of the two levers 16 and 19 and also the vertical adjustment 100

of the levers, both of the levers are mounted so that they may be swiveled to bring them into alignment and adjusted vertically to secure the proper relation. With this in mind, the bracket or fulcrum member 17 on which the lever 16 is mounted is provided with a round standard 24 fitted in a split clamping sleeve 25 secured to the outer shell 9 so that the fulcrum 18 may be given a slight swiveling adjustment or may be adjusted vertically to secure the proper relation of parts. Similarly, the fulcrum member 26 on which the lever 19 is pivotally mounted is provided with a round post 27 fitting in a clamping sleeve 28 on the bracket 20 whereby this post 27 may be given a swiveling adjustment or an up and down adjustment, as desired. Furthermore, both levers 16 and 19 may be given an additional swiveling movement, since the bracket 20 which carries the fulcrum post 26 is an integral part of an annular bonnet member 29 threaded onto the bushing 30 forming a lower part of the valve casing 31 so that this bonnet 29 can be given a swiveling adjustment about the axis of the valve casing 31. Similarly, the entire float chamber 32 may be given a swiveling adjustment about the vertical pipe 10 onto which the float chamber 32 is threaded so that by means of these various adjustments the proper height of the levers 16 and 19 and the proper relation with respect to each other may be secured.

In order to secure just the right counterbalancing effect for the float or bell 5, the lever 16 is provided with a screw extension 33 on which an adjustable weight 34 is mounted.

Coming now to a detailed description of the relay valve 4, which controls the connection of the cylinder 3 with the pressure and exhaust, this comprises a valve member 35 controlling the port 36 and thereby controlling the communication between the compressed air passage 37 and the passage 38 for the supply and exhaust for the cylinder 3 and a second valve member 39 for controlling communication between the common inlet and exhaust passage 38 and the exhaust passage 40. The arrangement and construction is such that on an upward movement of the valve stem 23 brought about by the action of the bell 5, the supply connection 37 will be open immediately after the exhaust connection 40 is closed and vice versa on the downward movement of the valve stem 23 the exhaust passage 40 will be opened immediately after the supply connection 37 is closed. This relation is brought about by having the upper supply valve 35 actuated by the lower exhaust valve 39 on upward movement of the latter and by having a passage 41 through the exhaust valve 39 which is closed the instant the upper end of the exhaust valve 39 comes in contact with the

lower end 42 of the supply valve 35. Clearance passages 43 are provided about the downward extension of the supply valve 35 to permit compressed air to pass the instant the supply valve 35 is forced from its seat 44. 70

The exhaust valve 39 has a substantially fluid-tight fit in the sleeve portion 45 of the valve casing. The valve stem 23 has a pivotal connection with the exhaust valve 39 at 46. A suitable packing is provided in the lower end of the valve casing around the valve stem 23, comprising a pair of packing rings or washers 47 held in engagement with their seats by means of a coil compression spring 48 therebetween. It will be seen that this arrangement is such that the packing is exposed only to the exhaust pressure and never to the supply pressure and such also that the packing will be in effect a water seal because of the water of condensation 85 which will trickle down in the lower end of the valve casing.

In operation, assuming that the piston 49 is in an upper position, or at least not in its lowermost position, and that the exhaust valve 39 is in its lower position or at least out of engagement with the lower end 42 of the supply valve 35, the cylinder 3 above the piston 49 will be in communication with the exhaust through the passages 38, 41 and 40 and the power piston 49 will move upwardly under the action of the weights 50 and 51 so long as this exhaust connection is open. This will cause the uptake damper 2 to open wider resulting in an increased draft and an increased suction in the bell 5 causing the bell to be lowered and the relay valve stem 23 to be raised. This upward movement of the valve stem 23 will in time cause the upper end of the exhaust valve 39 to engage the lower end 42 of the supply valve 35 closing the exhaust passage 41 through the exhaust valve 39 and preventing further upward movement of the power piston 49. Any further upward movement of the valve stem 23 will lift the supply valve 35 from its seat, thus admitting compressed air to the cylinder 3 above the piston 49 through the passages 43 and 38 and forcing the piston 49 down to cause a closing movement of the uptake damper 2. 100

The counterweight 51 is just heavy enough to operate the uptake damper 2 properly and is made as light as practicable in order that the damper may be readily operated by hand by means of the pull chain 52, when desired. The additional counterweight 50 is provided to insure the upward movement of the piston 49 when the cylinder above the piston is opened to exhaust and it will be noted that the arrangement is such that this exhaust 50 does not have to be moved when the damper 2 is operated by hand. Suitable pulleys 53 are provided over which the flexible elements 54 run. 110 120 125 130

It will be seen that the construction shown will maintain the draft substantially constant and that it will give a graduated action to the damper.

While I have shown and described but one embodiment of the present invention, it will be apparent to those skilled in the art that various modifications thereof may be made without departing from the spirit and scope 10 of this invention, and, therefore, I wish to be limited only by the scope of the prior art and the appended claims.

I claim:

1. A regulator construction comprising a liquid container, an open bottom container having its lower edge immersed in the liquid in the container and having its interior in communication with a source of variable pressure whereby said container is moved in accordance with variations of pressure, a power cylinder, a piston operating therein, a fluid pressure passage for supplying fluid for operating said piston, a fluid exhaust passage for said cylinder, and valve control 25 means for controlling said supply and exhaust passages controlled by the pressure-controlled movement of said container, and transmission between said container and valve means comprising a lever operated by 30 said container, and a second lever actuated by said first lever for operating said valve means, one of said levers being adjustable about a vertical axis to assist in bringing the levers into proper relation.

2. A regulator construction comprising a liquid container, an open bottom container having its lower edge immersed in the liquid in the container and having its interior in communication with a source of variable pressure whereby said container is moved in accordance with variations of pressure, a power cylinder, a piston operating therein, a fluid pressure passage for supply fluid for operating said piston, a fluid exhaust passage for 40 said cylinder, and valve control means for controlling said supply and exhaust passages controlled by the pressure-controlled movement of said container, and transmission between said container and valve means comprising a lever operated by said container, and a second lever actuated by said first lever for operating said valve means, both of said levers being adjustable about vertical axes to assist in bringing them into proper relation.

3. A regulator construction comprising a cylinder, a piston, and means for alternatively subjecting said piston to pressure and exhaust comprising a valve construction having a pressure chamber and an exhaust chamber, valve mechanism for controlling the communication between said chambers and cylinder, and means for operating said valve mechanism to control both pressure and exhaust comprising a valve stem extending

from the exhaust chamber to the atmosphere and a stuffing box surrounding said valve stem whereby the stuffing box is subjected only to exhaust pressure, said stuffing box being below the exhaust chamber whereby if steam is used as the medium the water of condensation will flow down into the stuffing box to provide a water seal packing.

4. A regulator construction comprising a cylinder, a piston, and means for alternatively subjecting said piston to pressure and exhaust comprising a valve construction having a pressure chamber and an exhaust chamber, valve mechanism for controlling the communication between said chambers and cylinder, and means for operating said valve mechanism to control both pressure and exhaust comprising a valve stem extending from the exhaust chamber to the atmosphere and a stuffing box surrounding said valve stem whereby the stuffing box is subjected only to exhaust pressure, said stem having a flexible portion without lost motion outside the exhaust chamber and an actuating lever pivotally connected with said flexible portion.

5. A regulator construction comprising an annular cup having inner and outer shell portions between which the liquid is contained, the space within the inner shell having a connection at its lower portion with a source of variable pressure, a bell or inverted cup forming a pressure chamber having its lower edge immersed in the liquid contained between the inner and outer shells, whereby said cup is moved in accordance with the variation in pressure, and a tubular member in communication with a draft gauge extending upwardly into the space within said inner shell to a point above the connection with the source of variable pressure whereby the draft gauge will be subjected to the variable pressure and whereby foreign substances dropped into the space within the inner shell will not readily find their way into the tube leading to the draft gauge.

6. A regulator construction comprising a liquid container, an open bottom container having its lower edge immersed in the liquid in the container and having its interior in communication with a source of variable pressure whereby said container is moved in accordance with variations in pressure, said liquid container having a removable imperforate cover and transmission from said open-bottom container to mechanism to be controlled thereby comprising a lever extending through the side of said liquid container below the edge of said removable cover and having an arm operating in the space between the cover and open-bottom container.

In witness whereof, I have hereunto subscribed my name.

JOHN M. LARSON.
